DOORSTOP

Harry O. Brenzikofer, West Los Angeles, Calif.

Application May 26, 1941, Serial No. 395,120

3 Claims.

(Cl. 16—86)

This invention is a stop of the type adapted for horizontal projection from a wall or baseboard for abutment by a swinging door so that impact is axially of the stop.

It is an object of the invention to provide a stop which is substantially rigid responsive to said axial impact, so as to provide a positive stop for the swinging door; but which is resiliently flexible responsive to impact transversely of the stop, so as to readily yield in the event of being laterally struck.

It is a further object of the invention to provide substantial rigidity responsive to said axial impact but with some resiliency at the extreme outer end of the stop, so as to cushion initial impact by the door and then positively arrest its swinging movement.

It is a still further object of the invention to provide resilient flexibility responsive to impact transversely of the stop, with a resiliently yieldable surface cushioning initial transverse impact and the entire stop then adapted to swing laterally responsive to said transverse impact.

The projecting stop thus cushions and then positively arrests a swinging door or other movable element, and in the event of being accidentally laterally struck, e. g. by a person, furniture, floor-cleaning equipment, etc., the stop initially cushions such transverse impact and then yields laterally.

Further objects of the invention will be readily understood from the following description of the accompanying drawing, in which:

Fig. 1 is a side elevation of the invention, partly in axial section.

Figs. 2 and 3 are transverse sections on the lines 2—2 and 3—3 respectively of Fig. 1.

Fig. 4 is a side elevation, partly in axial section, showing a modification of the invention.

The stop comprises a base 1 adapted for mounting on a wail, baseboard, etc., and having a horizontally projecting shank 2. The outer end of the shank is adapted for abutment by a swinging door or other movable element, with this impact axially of the shank; and the outer end of the shank is preferably adapted to cushion initial axial impact while the major portion of the shank is substantially rigid responsive to said axial impact. The shank is also adapted to laterally resiliently flex in the event of accidental transverse impact, and the outer surface of the shank preferably cushions initial transverse impact.

As an instance, the shank includes a helical spring 3, preferably of spring wire, having a

normally straight axis extending substantially the full length of the shank 2, with successive coils of the spring normally substantially abutting axially of the spring. The spring is thus normally at substantially maximum compression providing a positive stop responsive to axial impact; but responsive to transverse impact the spring is adapted for relative flexing of its coils for laterally swinging the spring.

10 The end of the spring 3 which is at the inner end of the shank 2 is fixed to the base 1, with the spring projecting horizontally from the base. For this purpose, the base is preferably a rigid structure of metal or the like having attaching means such as a screw 4 projecting from one face; and the opposite face of the base is preferably concentrically annularly recessed as shown at 5, with this annular recess surrounding a stud 6 which projects integrally from the base. The inner end of the helical spring 3 is received in the recess 5, and may be fixed therein by laterally expanding the stud 6 for clamping engagement with the spring.

To permit this lateral expansion of the stud 6, its outer end is preferably transversely weakened, e. g. by axially recessing the outer end of the stud as shown at 7. When the spring is in place a punch tool may be inserted via the bore of the spring so that the inner end of the tool seats in the recess 7 and the outer end of the tool is accessible beyond the outer end of the spring for operating the tool, e. g. striking the same, so as to laterally expand the weakened outer end of the stud 6.

35 The shank 2 preferably also includes a cushioning sleeve 8 of rubber or the like, providing a peripheral cushion 9 and an outer end cushion 10 for the spring 3. After the spring has been fixed in place projecting outwardly from the base 1, and preferably with an abutment cap 11 at the outer end of the spring, the cushioning sleeve may be molded in place with the molded rubber filling the bore and surrounding the spring and also projecting radially and axially 40 beyond the cap 11, preferably with a reinforcing annulus 12 embedded in the periphery of the end cushion 10. The inner end of the sleeve 8 is molded to the outer face of the base 1, preferably with the outer face of the base forming a concave surface 13 surrounding the annular recess 5 and preferably recessed, e. g. by concentric grooves 14, so as to provide retaining means for the complementary inner end of the molded cushioning sleeve.

45 The surface 13 and the proximate inner end of

the peripheral cushion 9 preferably have appreciable radial dimension, and the peripheral cushion preferably tapers to reduced thickness toward its outer end where it merges into the radial enlargement of the end cushion 10. The radial thickness at the inner end of the sleeve 8 thus laterally reinforces the spring 3 where it initially projects from the base 1, so that responsive to transverse impact the shank 2 is adapted to laterally resiliently flex, without abrupt flexure immediately adjacent the base 1 as might result in permanent lateral distortion of the spring 3, but with gradually increasing lateral flexure toward the extreme outer end of the shank.

The base 1 of the stop is operatively mounted by its screw 4 so that its shank 2 projects in direction for abutment by the element such as a door for which the stop is provided, with the parts relatively positioned so that this abutment results in impact axially of the stop. The spring 3 being normally at substantially maximum axial compression provides a positive stop responsive to this axial impact, with the impact preferably initially cushioned at 10. The stop is thus adapted for normal functioning.

In the event of the stop being accidentally laterally struck it readily yields so as to prevent injury to a person, or marring furniture, or damaging equipment such as a vacuum cleaner. Responsive to such transverse impact the outer end of the shank 2 swings laterally relative to its fixed inner end, with gradually increasing curvature along the axis of the shank toward its outer end and with the impact preferably initially cushioned at 9; and when the shank has been swung so as to disengage whatever has caused the transverse impact it immediately returns to its normal position due to the resiliency of its spring 3 and its cushioning sleeve 8. The stop, in addition to its normal functioning responsive to axial impact, is thus adapted to readily swing laterally out of the way responsive to transverse impact.

While specifically described as a stop for a swinging door, with the stop mounted on a wall or baseboard, it will be understood that the stop is generally applicable for relatively movable elements, with the stop projecting from either element and adapted for axial impact for arresting said relative movement and also adapted to swing laterally out of the way responsive to accidental transverse impact.

At Fig. 4 a modification is shown in which the cushioning sleeve is detachably mounted on the spring instead of being molded thereto. The construction and operation is the same as pre-

viously described (with corresponding parts indicated by the same reference numerals with the exponent *a*), except for the following modifications:

5 The cushioning sleeve 8a has a bore which is open at the inner end of the sleeve, with the abutment cap 11a embedded in the sleeve at the closed opposite end of its bore; and after the spring 3a has been fixed in place projecting from the base 1a the cushioning sleeve is adapted for snug reception over the spring, with the cap 11a abutting the outer end of the spring, and with the inner end of the cushioning sleeve detachably fixed to the base 1a. This detachable connection preferably comprises an external annular flange and groove 20-21 at the periphery of the base 1a, adapted for resiliently detachable engagement by a cooperating annular groove and internal flange at the inner end of the sleeve 8a.

20 I claim:

1. In a stop for relatively movable elements, a base adapted to be fixed to one of said elements and having a projecting stud and an annular recess surrounding the stud at the outer face of the base, and a helical spring having one end snugly received in the annular recess with the major portion of the spring projecting outwardly from the base for axial impact by the other of said elements, the stud being adapted for radial expansion for clamping the inner end of the spring in the annular recess.

2. In a stop for relatively movable elements, a base adapted to be fixed to one of said elements and having a projecting stud and an annular recess surrounding the stud at the outer face of the base, and a shank adapted for axial impact by the other of said elements and comprising a helical spring and a sleeve of resilient material, the spring being normally at substantially maximum axial compression with one end of the spring received in the annular recess so that the major portion of the spring projects outwardly from the base, the stud being adapted for radial expansion for clamping the inner end of the spring in the annular recess, and the resilient sleeve surrounding the periphery and the outer end of the spring and fixed at its inner end to the base.

3. In a stop, a base, a projecting helical spring fixed at its inner end to the base, an abutment cap overlying the outer end of the spring, and a shank of resilient material surrounding the spring and the abutment cap and fixed at its inner end to the base.

50 HARRY O. BRENZIKOFER.
